UNITED STATES PATENT OFFICE.

ELMER ELLSWORTH REED, OF CHILlicothe, Missouri.

INSIDE BRACE FOR SILOS AND TANKS.

1,074,645.

Specification of Letters Patent.

Patented Oct. 7, 1913.

Application filed December 6, 1912. Serial No. 735,303.

To all whom it may concern:

Be it known that I, ELMER E. REED, a citizen of the United States, residing at Chillicothe, in the county of Livingston and State of Missouri, have invented certain new and useful Improvements in Inside Braces for Silos and Tanks, of which the following is a specification.

My invention relates to a device to be mounted within a silo, tank, barrel or the like, to hold the staves of the same in their proper positions, so that they will not be distorted or warped upon shrinking, and the different parts of the silo, tank or barrel will be prevented from falling apart.

An important object of this invention is to provide a device of the above mentioned character, which is simple in construction and which will exert a constant yielding pressure upon the inner surface of the staves of the silo, tank or barrel, to properly hold them in place.

A further object of this invention is to provide a device of the above mentioned character, which is circumferentially adjustable, to fit within silos, tanks or barrels of different sizes.

A further object of this invention is to provide a device of the above mentioned character, which is simple in construction, strong, durable, and cheap to manufacture.

Other objects and advantages of this invention will be apparent during the course of the following description.

In the accompanying drawings forming a part of this application and in which like numerals are employed to designate like parts throughout the same, Figure 1 is a plan view of the complete device, parts thereof being shown in section and parts removed, Fig. 2 is an enlarged detail section taken on line 2-2 of Fig. 1 and looking in the direction of the arrows, Fig. 3 is a transverse sectional view taken on line 3-3 of Fig. 1, and Fig. 4 is a similar view taken on line 4-4 of Fig. 2.

In the drawings, wherein for the purpose of illustration, I have shown a preferred embodiment of my invention, the numeral 5 designates a plurality of ring-sections, which form in effect a ring. I have shown four of these ring-sections, but it is to be understood that any other suitable number may be employed. I have found that satisfactory results are obtainable by employing

two ring-sections 5. Each of the ring-sections 5 may preferably be circular in cross-section, as shown in Fig. 2, although satisfactory results are obtainable by forming them square, rectangular, or any other shape in cross-section. The adjacent ends of the ring-sections 5 overlap, and are freely movably mounted within sleeves or sockets 6, as shown. It is thus seen that the ring-sections 5 form a readily expandible and contractible ring.

The numeral 7 designates a socket or housing, which is connected with each of the ring-sections 5. Each of these sockets 7 is preferably formed rectangular in cross-section, although not necessarily restricted to this shape, and comprises two parts 8. The parts 8 are provided with longitudinal flanges 9, connected by bolts 10, as shown. The outer ends of the parts 8 are provided with oppositely arranged curved recesses 11, which receive therein the ring-section 5. By this means the socket 7 is pivotally connected with the ring-section 5 so that the socket may be swung in a vertical plane with relation to the ring-section. The outer edge or periphery of the ring-section preferably extends beyond the outer end of the socket 7, to engage a stave 12 of the silo tank or barrel, as shown. Mounted within each socket 7 are a plurality of suitably stiff coil springs 13, the outer ends of which engage a plate 14, as shown. The inner ends of these springs engage a plate 15. While I have shown two coil springs 13, it is to be understood that the invention is in no sense restricted to any particular number of coil springs, as more than two may be employed or only one, depending upon the strength and stiffness of the same. Each socket 7 is slidably mounted upon a radially disposed arm or rod 16, which is preferably rectangular in cross-section although the same may be formed in any other shape in cross-section.

The numeral 17 designates a central hub or casting, which is X-shaped, as shown. This hub carries a plurality of pairs of radially disposed extensions or arms 18, corresponding in number to the rods or arms 16, as shown. Each rod 16 has its inner end extending into the corresponding pair of extensions 18, the inner end of the rod being tapered or pointed to properly fit within a portion of the hub 17, as shown. Each 110

of the rods or arms 16 is normally held within the pair of extensions 18 by a loop 19, which is adapted to be slid upon the pair of extensions 18 and off of the same 5 upon the rod 16. When the loop 14 is disposed upon the pair of extensions 18, the same serves to hold the rod or arm 16 between the extensions 18, and also serves to form a sort of pivotal connection between 10 the rod 16 and the hub 17, so that the hub may be slightly raised with relation to the ring-sections 5.

In the use of the device, the hub 17 is moved slightly above the ring sections 5, 15 whereby such ring sections may be forced inwardly to suitably contract the ring formed by the same. This having been done, the device is inserted within the silo, tank or barrel, subsequently to which the hub 17 is forced downwardly to lie in the same horizontal plane with the ring-sections. It is thus seen that upon forcing the hub 17 downwardly, the rods or arms 16 will be moved outwardly to engage and compress 20 the springs 13. These springs being thus placed under tension force the ring-sections outwardly, thus causing the expansion of the ring formed by the same. The ring-sections 5 will exert a continuous yielding outward 25 pressure upon the inner surface of the staves of the silo, tank or barrel, retaining them firmly in engagement with the hoops surrounding them. These staves are thus securely held in place and accordingly prevented 30 from being distorted or warped upon shrinking when drying. The staves and hoops are also retained in their assembled position and the silo, tank or barrel may be again used by properly tightening up the 35 hoops to bring the staves in close relation. 40

It is to be understood that the form of my invention herewith shown and described, is to be taken as a preferred example of the same, and that certain changes in the shape, 45 size and arrangement of parts may be resorted to without departing from the spirit

of the invention or the scope of the subjoined claims.

Having thus fully described my invention, I claim:—

1. In a device of the character described, an expandible and contractible ring, radially disposed rods connected therewith, a hub carrying pairs of spaced extensions to receive the inner ends of the rods therebetween, and loops to be moved onto and off of the pairs of extensions. 55

2. In a device of the character described, an expandible and contractible ring, sockets connected therewith, radially disposed rods 60 mounted to reciprocate within the sockets, coiled springs disposed within the sockets between the ends of the rods and the ring, and means connecting the inner ends of the rods. 65

3. In a device of the character described, a plurality of ring-sections having their adjacent ends overlapping, sleeves surrounding the overlapping adjacent ends, a socket pivotally connected with each of the ring sections, a rod mounted to reciprocate within each socket, a suitably stiff coil spring disposed within each socket between the outer end of the rod and the ring section, and means connecting the inner ends of the rods. 70 75

4. In a device of the character described, an expandible ring, a plurality of sockets connected therewith, each socket comprising two parts having openings cut in their outer ends to receive portions of the ring, 80 bolts connecting the two parts, a compressible coil spring mounted within each socket, a reciprocatory rod mounted within each socket, and a hub connecting the inner ends of the rods. 85

In testimony whereof I affix my signature in presence of two witnesses.

ELMER ELLSWORTH REED.
